GAME TABLE

Paul Kotler, 35 Webster St., Irvington, N.J. 07111

Filed Apr. 30, 1965, Ser. No. 85,089

Term of patent 14 years

(Cl. D34—3)

FIG. 1 is a perspective view of a billiard table or the like showing my new design;

FIG. 2 is a fragmentary enlarged side elevational view of the ball holding portion.

The dominant features of the design reside in the portions shown in full lines. The balls that are shown in broken lines are thus shown for illustrative purposes. The sides of the table not shown are substantially plain.

The essential feature of my design resides in the combination on the table disclosed of the glass panel on one of the sides having opaque sections above and below the central transparent area which displays the accumulated balls in an angular arrangement, all as shown.

I claim.

The ornamental design of a game table, substantially as shown and described.
